Attorneys

UNITED STATES PATENT OFFICE.

AUGUST SCHUCHARDT, OF RUHLA, GERMANY.

CLUSTER LAMP SOCKET.

Application filed April 11, 1924. Serial No. 705,843.

To all whom it may concern:

Be it known that I, AUGUST SCHUCHARDT, a citizen of the German Republic, residing at Ruhla, Thuringia, Germany, have invented certain new and useful Improvements in Cluster Lamp Sockets, of which the following is a specification.

This invention has for its object to improve the construction of cluster lamp sockets in such a manner that it is considerably simplified, of compact shape and comprises as few elements as possible and a central insulation body on which all the terminals, or boss and lamp sockets are fixed so that by the unscrewing of a few screws all the elements can be removed.

An embodiment of the invention is shown, by way of example on the accompanying drawing, in which:—

20 Fig. 1 is a longitudinal section.

Fig. 2 is a horizontal section on line A—B of Fig. 1.

Fig. 3 is a vertical section on line C—D of Fig. 1.

25 The cluster lamp socket comprises an insulating body *a* which has, on its lower side, means for supplying current to the incandescent lamps. This insulating body *a* carries on its top part a boss *b* of insulating material which contains the current receiving elements. These elements are the outer terminal *c* and the central terminal *d*. The outer terminal *c* is electrically connected with a conductor *g* which has flaps *g'* leading to the central terminals *h* of the two lamps. The central terminal *d* of the boss *b* is held by a screw bolt *i* the lower end of which engages with a metal yoke *k* which has two flaps *k'* into each of which a screw

40 *m* is screwed, said screws being fixed in the corresponding sleeve terminals *l* for the lamps. Each sleeve terminal *l* is enclosed in a socket *n*, said sockets being mounted each in a cavity *o* of the insulating body *a* and held in the sleeve terminals *l* by commonly used standard holder rings *p*. By the boss *b* a good transmission of current is ensured e. g. from the outer terminal *c* to conductor *g* and the flaps *g'* of the same, hence to the central terminals *h* of the lamps and from the central terminal *d* of the boss, screw bolt *i* and conductor *k* and the flaps *k'* of

the same to screws *m* and the sleeve terminals *l*. In the sleeve terminals *l* disks *q* of insulating material of convenient thickness are located which are held by the central contact screws and designed to insulate the central terminals *h* from the sleeve terminals *l* (see Figs. 1-3).

I claim:—

A cluster lamp socket comprising, an integral body of insulating material having a cavity in its top and sockets formed in its bottom, an upper conductor located in said cavity, said body and conductor being formed with perforations leading from said cavity to each of said sockets and said body being formed with a central perforation, and a lower conductor held against the under face of said body about said central perforation, in combination with a longitudinally centrally perforated boss of insulating material, a screw passing through the perforation in said boss and the aligned central perforation in said body and engaging said lower conductor to hold said boss tightly seated in said cavity and to hold said boss, body and lower conductor rigidly together in assembled relation, an outer terminal on said boss extending over the lower end face thereof adjacent the edges thereof to seat upon, and make electrical contact with, the upper conductor, two lamp sockets respectively seated in the respective sockets in said body and comprising each a central insulating block, a terminal sleeve, and a central contact, means electrically connecting the respective terminal sleeves to said lower conductor, screws respectively extending from said cavity through the respective perforations in said upper conductor and said body to the respective sockets and through the respective insulating blocks of the respective lamp sockets therein, and engaging the central contacts respectively of the respective lamp sockets to hold said lamp sockets firmly in the sockets of said body and also to establish electrical connection between said upper conductor and the respective central contacts of the respective lamp sockets.

In testimony whereof I affix my signature.

AUGUST SCHUCHARDT.
